UNITED STATES PATENT OFFICE.

WILLIAM L. BARRON, OF NEW YORK, N. Y., AND FRITZ E. OSOL, OF ELIZABETH, NEW JERSEY, ASSIGNORS TO THE SINGER MANUFACTURING COMPANY, A CORPORATION OF NEW JERSEY.

SEWING-MACHINE.

1,388,914.

Specification of Letters Patent. Patented Aug. 30, 1921.

Application filed November 23, 1915. Serial No. 62,951.

To all whom it may concern:

Be it known that we, WILLIAM L. BARRON and FRITZ E. OSOL, citizens of the United States, residing at New York, in the county 5 of New York and State of New York, and Elizabeth, in the county of Union and State of New Jersey, respectively, have invented certain new and useful Improvements in Sewing-Machines, of which the following 10 is a specification, reference being had therein to the accompanying drawings.

This invention has for its object to provide simple and effective mechanism for laying a covering thread transversely in advance of 15 a plurality of reciprocating needles in the formation of an ornamental seam similar to that shown in the United States patent to Joseph Berger, No. 1,060,526, of April 29, 1913.

20 The preferred form of the present improvement is embodied in a multiple needle chain-stitch machine comprising a plurality of thread carrying needles coöperating with a single reciprocating thread-carrying looper 25 operating beneath the work-plate.

The covering thread mechanism is mounted upon the presser-bar and comprises a thread-carrying implement adapted for movement at one side only of the line of 30 seam and substantially parallel with the line of feed, and a spreader or looping-finger arranged for movement across the line of seam, these implements traversing intersecting paths, one of which is rectilinear and the other arcuate. Mounted for 35 movement upon the presser-bar is a reciprocating member provided with an arm to which is rigidly secured the thread-carrying implement. Fulcrumed upon the presser- 40 bar is a rocker to one arm of which is rigidly secured a spreader, the other arm of the rocker having a link-connection with the rectilinearly reciprocating member from 45 which it receives its movements. The reciprocating member, which imparts opera- 50 tive movements to the thread-carrying implement and spreader, is driven by a suitable connection with the needle actuating shaft. When the presser-bar is raised the thread- 55 handling mechanism is lifted bodily without disturbing the relative timing of the thread-engaging implements.

In the accompanying drawings, Figure 1 is a front end elevation of a machine embodying the present improvement, with the

face-plate removed and the throat-plate in section. Fig. 2 is a perspective view showing the needles and covering-thread mechanism. Fig. 3 is a detail perspective view of the rocker carrying the spreader and its 60 link-connection with the reciprocating member, and Figs. 4 and 5 are perspective views illustrating the method of coöperation of the thread-laying devices with the needles.

The machine is or may be provided with 65 a stitch-forming mechanism constructed substantially in accordance with the United States patent to William H. Hugg, No. 1,005,645, of October 10, 1911. It is constructed with the usual base 1, and bracket-arm comprising the hollow standard 2 and tubular overhanging arm, of which the head 3 only is shown, and in which is journaled 70 the vertically reciprocating needle-bar 4 provided with the needle-clamp 5 carrying 75 the two eye-point needles 6. The needle-actuating rock-shaft 7 journaled in the overhanging bracket arm carries at its forward end a collar 8 formed with a crank-arm 9 provided with a crank-pin 10 connected by 80 means of the usual link 11 with a rearwardly projecting stud carried by the collar 12 clamped upon the needle-bar 4, through which connections the needles 6 receive their operative movements from the rock-shaft 7. 85 Journaled upon the base 1, beneath the work-plate is the looper-carrier 13 provided with the lower thread-carrying looper 14 which coöperates with the needles 6 in the formation of stitches, as fully described in the 90 patent to Hugg before referred to.

Journaled in the bracket-arm head 3 is the presser-bar 15 normally pressed downward by a spring, of which only the end 16 is shown, and having secured near its lower 95 end by means of the fastening screws 17, the bearing block 18, the reduced lower end of the presser-bar having secured thereon by means of the fastening screw 19 the usual presser-foot 20.

100 Adapted to slide within the support or bearing-block 18 is a rectilinearly reciprocating member 21 having an upwardly extending arm 22 apertured to receive a screw-stud 23 upon which is journaled one end of an endwise-adjustable link 24 whose other end is pivotally connected to the depending arm of a rocker 25 journaled upon a screw-stud 26 carried by the bracket 27 which is rigidly secured to the bracket-arm head 3 110

by the fastening screws 28. The lateral arm of the rocker 25 is connected by a bent link 29 with an eccentric stud 30 carried by the collar 8.

- 5 Projecting laterally from the reciprocating member 21 is a forwardly extending arm 31 to which is secured, by means of the transverse set-screw 32, the downwardly extending thread-carrying implement 33 which is 10 formed with a rearwardly directed end having a covering-thread guiding aperture 34 at its lower extremity. Fulcrumed on the screw-stud 35, depending from a flat seat on the under side of the bearing-block 18, is a 15 rocker 36 whose rearwardly extending arm carries a pivotal pin 37 passing through one end of a link 38 whose other end is apertured to receive the screw-stud 39 depending from the rear end of the reciprocating member 21. 20 Secured in a suitable socket on the free end of the rocker-arm 36 by means of the set-screw 40 is the spreader-arm 41 whose free end is formed with a suitable thread-hook 42 to engage and spread the covering-thread 25 loop.

The link 38 thus constitutes a direct driving connection between the member 31 supporting the thread-carrying implement 33 and the rocker arm 36 supporting the 30 spreader 41 and insures the maintenance of the correct relative timing of the thread handling implements one of which is suitably actuated by the driving element on the main-shaft.

- 35 In the use of the machine, the under thread looper is threaded in the usual manner and the needle-threads *a* and *b* passed through the eyes of their respective needles 6. The covering-thread *c* is led from the 40 source of supply through a suitable tension (not shown) to a fixed thread-guide 43 upon the inner side of the bracket-arm head 3 from which it is led through the delivery aperture 34 of the thread-carrying implement 33. The material *m* having been introduced between the presser-foot 19 and the 45 throat-plate 44, the machine is set in operation.

During the descent of the needles (Fig. 4), 50 the spreader or looping finger 41 begins its retractive movement from advance or spreading position across the line of seam while the thread carrying implement 33 begins its forward movement parallel therewith the 55 points of the needles having previously descended below the covering thread leading from the implement 33 to the work. As the needles 6 pass below the throat-plate 44 and begin to rise to form their loops for seizure 60 by the threaded loop-taker 14, the thread-carrying implement 33 and the spreader 41 have reached their respective extreme retracted positions, and as they resume their advance movements, the spreader 41 engages 65 and forms a loop in the covering thread *c*

which it carries across the line of seam. While the spreader is moved in this manner, the needles 6 are completing their ascent and the thread-carrying implement 33 begins its receding movement. During the rise 70 of the needles, the thread-carrying implement 33 draws the covering thread *c* taut across the line of seam but at a slight angle thereto so that one of the needles will be in front of the covering-thread while the other will be in its rear, the two implements acting in conjunction to hold and spread the covering thread *c* for passage of the needles in their succeeding descent.

As the stitching continues, the thread-carrying implement and spreader continue to perform their reciprocations, one in a rectilinear path at one side only and parallel with the line of seam and the other in an arcuate path transversely thereto and across the line of seam, each receiving a to-and-fro movement for every reciprocation of the needles so that loops of covering thread are laid intermediate the needle-paths back and forth across the line of seam similar to that 90 of the looper-thread upon the lower face of the fabric, the looper receiving the usual endwise and sidewise movements in inter-looping its thread with the needle-threads. In the finished seam, as represented in Figs. 95 4 and 5, loops of covering thread *c* are laid alternately at opposite sides of the stitch-line and each is entered by a thread-loop of the adjacent needle through both of which needle-thread loops is passed a loop of 100 looper-thread, not shown.

The machine is provided with any usual or suitable feeding mechanism and comprises the feed-rocker 45 operatively connected with the feed-bar 46 and provided with the feed-dog 47 adapted to engage and advance the material through suitable slots in the throat-plate 44.

Having thus set forth the nature of the invention, what we claim herein is:— 110

1. In stitch-forming mechanism, the combination with a needle and means for reciprocating the same, of a presser-bar, a reciprocating member adapted for movement upon said presser-bar, a thread-carrying implement and a spreader, one of which is mounted on the presser-bar and the other upon the reciprocating member, means including said reciprocating member for imparting movements to said thread-carrying 115 implement, and a connection between said reciprocating member and said spreader for actuating the latter.

2. In stitch-forming mechanism, the combination with a needle and means for reciprocating the same, of a reciprocating member and thread-laying means comprising two co-operative thread-laying implements, one movable upon a substantially fixed fulcrum 125 across the line of seam and the other mount- 130

ed upon said reciprocating member and confined to movement at one side of the line of seam, means including said reciprocating member for imparting movements to one of 5 said thread-laying implements, and a connection between said reciprocating member and the other thread-laying implement for actuating the latter.

3. In stitch-forming mechanism, the combination with a needle and means for reciprocating the same, of a presser-bar, a movable member mounted upon said presser-bar, a thread-carrying implement mounted upon said movable member and confined to 10 movement at one side of the line of seam, a rocker journaled upon said presser-bar and having operative connections with said movable member, a spreader carried by said rocker and adapted for movement across the 15 line of seam, and means including said movable member for imparting movements to said thread-laying implement and spreader.

4. In stitch-forming mechanism, the combination with a needle and means for reciprocating the same, of a presser-bar, a reciprocating member movably mounted upon said presser-bar, a thread-carrying implement mounted upon said reciprocating member, a spreader fulcrumed upon said presser-bar and having operative connection with said reciprocating member to move said spreader across the line of seam, and means for imparting movements to said thread-laying 30 implement and spreader.

35 5. In stitch-forming mechanism, the combination with a needle, a rock-shaft, connections between said rock-shaft and the needle for operating the latter, of a presser-bar, a rectilinearly reciprocating member movably mounted upon said presser-bar, operative connections between said rock-shaft and said reciprocating member, and a thread-carrying implement and a spreader operatively connected with said reciprocating member.

45 6. In stitch-forming mechanism, the combination with a needle, a rock-shaft, connections between said rock-shaft and the needle for operating the latter, of a presser-bar, a rectilinearly reciprocating member movably mounted upon said presser-bar, operative connections between said rock-shaft and said reciprocating member, and a thread-carrying implement and a spreader operatively connected with said reciprocating member, one 50 of which is mounted upon the reciprocating member and the other mounted independently thereof.

7. In a sewing machine, in combination, a reciprocating needle, an actuating shaft 60 therefor, a pair of thread-handling implements co-operating with one another to lay a covering thread across the line of seam, one of said implements being mounted for movement across the line of seam and the other 65 of said implements being mounted for move-

ment on one side only of said line of seam, a movable support for one of said implements, means for actuating said support from said shaft, a support for the other implement, and a connection independent of said 70 actuating means between the movable support and the support for the other implement for actuating the latter.

8. In a sewing machine, in combination, stitch-forming mechanism comprising a 75 needle and means for reciprocating the same, a covering thread-carrier, a movable support therefor, means for reciprocating said support to move said carrier at one side only of the line of seam, and a looping finger 80 movable across the line of seam and co-operating with said thread-carrier to lay its covering thread across the line of seam, said looping finger being connected with and actuated by said support. 85

9. In a sewing machine, in combination, stitch-forming mechanism comprising a needle and means for reciprocating the same, a presser-bar, a covering thread-carrier sustained by the presser-bar and confined to a 90 path of movement at one side only of and substantially parallel with the line of seam, a support therefor, means for reciprocating said support, and a looping finger actuated by the support for said thread-carrier and co-operating therewith to lay a covering thread 95 across the line of seam.

10. In a sewing machine, in combination, a reciprocating needle-bar carrying a plurality of needles arranged in a plane transverse to the direction of feed, means to reciprocate said needle-bar, an embroidery-thread carrier movable in a path substantially parallel with the direction of feed, a reciprocating support therefor, means for 100 reciprocating said support, and a co-operating looping finger movable in a path transverse to the movements of said carrier and actuated from said support. 105

11. The combination with a work-support, 110 a feed, a presser-foot, a presser-bar, needles and complementary stitch-forming mechanism, of a covering thread mechanism including a thread-carrying implement, a support mounted upon the presser-bar and movable up and down therewith, a reciprocating member mounted in said support, a thread-carrying implement mounted upon said reciprocating member, an actuating shaft, connections between the actuating shaft and the 115 reciprocating member for imparting operative movements to the latter, a spreader pivotally mounted upon said support and co-operating with said thread-carrying implement, and a direct connection between said 120 reciprocating member and said spreader for actuating the latter. 125

12. The combination of a work-support, a feed, a presser-foot, a presser-bar carrying said presser-foot and covering thread mecha- 130

nism including a thread-carrying implement movable in a direction substantially parallel with the line of feed, a spreader coöperating therewith and movable in a direction substantially at right angles to the line of feed, means for supporting said thread-carrying implement and spreader on the presser-bar whereby the same are moved up and down therewith through the action of the feed on the presser-foot and for removing and inserting the work, a reciprocating member upon which one thread handling element of the covering thread mechanism is mounted, actuating means for said reciprocating member, and a connection independent of said actuating means between the reciprocating member and the other thread-handling element for actuating the latter.

13. The combination with a work-support, a feed, a presser-foot, a presser-bar, needles, and complemental stitch-forming mechanism, of a covering thread mechanism including a thread-carrying implement movable in a direction substantially parallel with the line of feed, a spreader coöperating therewith, a reciprocating member movable up and down with the presser-bar, actuating means for said reciprocating member, and devices connected with said reciprocating member independently of said actuating means for actuating said thread-carrying implement and spreader.

In testimony whereof, we have signed our names to this specification.

WILLIAM L. BARRON.
FRITZ E. OSOL.
